Jules Decat, Montrouge, France

Application October 11, 1954, Serial No. 461,476

Claims priority, application France December 2, 1953

7 Claims. (Cl. 198—7)

The present invention relates to improvements in mechanical shovellers.

In accordance with the invention, the frame supporting the scraper chain is constituted by two beams pivotally connected to one another at one end. The beam nearer the discharge end of the scraper chain is pivotally connected at its other end in a trough, which is mounted on a carriage serving for the shifting of the shoveller as a whole. These beams are preferably made from tubular elements assembled to form a framework of generally rectangular form. The beam, situated at the pick-up end of the scraper chain, is suspended on this trough, through the intermediary of a collar surrounding the free end of this beam and connected by ties to a jib, pivotally mounted on the forward extremity of the trough, so that the beam can be raised or lowered at will, by operation of the jib and through a cable and a winch mounted on the trough.

The scraper chain, passing over a drive pinion and over a tensioning pulley, which are mounted at the opposite ends of the frame of the shoveller, is also guided, where it passes the pivotal connection of these beams, by two rollers, each mounted at the end of each of these beams near the pivotal connection. This arrangement prevents the chain from rubbing on the pivotal connection of the beams and decreases the sharpness of curvature of the chain in this region.

Stops, the position of which are adjustable, mounted on the trough, limit the descending movement of the end of the beam mounted in this trough, in the vicinity of its pivotal connection with the other beam, in order to prevent the chain from catching on the lip of the trough at its entry into the latter.

The trough is itself pivotally connected on the chassis of the carriage, and can be raised or lowered thereon, by means of an articulated system actuated by a lever, in order to permit of resting the front lip of the trough upon the ground or of raising it to a certain height for the movement of the shoveller.

The invention also relates to the special construction of the scraper chain, as will be described hereinafter in greater detail.

The attached drawings represent, by way of example, a form of embodiment of the shoveller according to the invention.

Figure 1 is a side elevation of the shoveller.

Figure 2 is a plan view corresponding thereto, but with certain parts omitted for the purpose of clarity of the drawings.

Figure 3 is a perspective view of a link of the scraper chain.

Figures 4 and 5 are perspective views showing the trough respectively in its lowered position and in its raised position in relation to the chassis of the supporting carriage, and

Figures 6 and 7 are corresponding views, in side and end elevation, of the trough in its lowered position.

2

The shoveller comprises a frame formed by two beams *a* and *b*, which are pivotally connected to one another at one end by a spindle *c*; the beam *b* is pivotally connected at its opposite end by a spindle *b*¹ in a trough *d*, which is itself mounted on a carriage *e* serving for the shifting of the shoveller as a whole.

Each of the beams *a* and *b* is formed of tubular elements (longitudinal and cross members), connected with one another in any appropriate manner, for example by welding, to form a frame of generally rectangular form.

The beam *a* carries, at its rear end, opposite to the articulation *c*, a shaft *a*¹ with a tensioning roller *f* for the endless scraper chain *g*; the latter passes, at the opposite end of the frame of the shoveller, over a drive pinion *h*, fixed on a transverse shaft *h*¹, journalled at *h*², *h*² in the trough *d*; this shaft *h*¹ also carries a chain sprocket *h*³, driven by a chain *h*⁴ which is itself driven, through a speed-reduction gear arrangement *h*⁵, by a motor *h*⁶, supported by the trough *d*.

20 The spindle *b*¹ for the pivotal connection of the beam *b* on the trough, instead of being situated, as shown in the drawing, in the vicinity of the shaft *h*¹, could coincide therewith.

The trough *d*, made of sheet metal, is of U shape in cross section (as may be seen more clearly from Figure 7); it is reinforced on its sides by angle irons *d*¹, and at its bottom by inclined plates *d*², in order to conform to the shape of the scraper chain.

25 Each of the beams *a* and *b* carries, at its end near the pivotal connection *c* of these beams, on a transverse shaft *a*², *b*², a roller *a*³, *b*³, respectively; these two rollers, which are situated on opposite sides of the spindle *c*, serve to guide the scraper chain *g*, preventing it from rubbing on this spindle *c* and diminishing the sharpness of curvature of the scraper chain *g* where it passes through this region.

30 The beam *a* is supported, at its free extremity, by a collar or stirrup *i*, surrounding this beam and connected by two ties *i*¹ to the upper end of a double jib *i*², pivotally connected on the rear end of the trough *d* at *i*³; this jib can be drawn up by means of a pulley *i*⁴, by a cable *i*⁵ passing over this pulley, the stationary length of the cable being fixed to the trough *d* at *i*⁶, while the movable length is wound on a pulley-drum *i*⁷; this pulley is actuated by a hand wheel *i*⁸, which can be locked by a bolt (not shown).

35 By winding the cable *i*⁵ upon the pulley-drum *i*⁷, it is possible to raise the beam *a* until it is brought into a position approaching the vertical.

40 The direction of rotation of the shaft *h*¹ and of the drive sprocket *h* for the scraper chain *g* is such that the lower run of this chain moves (from left to right in Figure 1) from the tensioning roller *f* towards the guide rollers *a*³, *b*³ and the toothed drive sprocket *h*.

45 This chain *g* carries (Figure 3) scrapers *g*¹, provided with cutting teeth *g*², for tearing away hard or compact products; each scraper carries a rear tail *g*³, bearing upon the corresponding link of the chain.

50 The shaft *a*¹ supporting the tensioning roller *f* at the rear end of the beam *a* carries at its ends cutting discs *a*⁴, intended to slice into the material on either side of the scraper chain, in order to facilitate its removal by the scraper chain, when this material is hard and compact (for example in the case of clay or manure).

55 Two stops (Figure 1), constituted by threaded rods *b*⁴ mounted in parts forming nuts fixed on the rear edges of the trough *d*, support the two longitudinal members of the beam *b*, in the vicinity of the pivotal connection *c* of the two beams *a*, *b*, in order to prevent the scraper chain *g* from catching on the lip *d*³ at the rear extremity of the trough.

This trough d is pivotally connected (see Figures 4 to 7) in the vicinity of its front end, on the chassis of the carriage e at d^4 , so that it can rock and permit the rear lip d^3 of the trough to rest upon the ground (Figures 1 and 4). In the vicinity of its rear extremity (to the left in the drawing), the trough d is supported by a transverse sleeve d^5 welded to the bottom of this trough (Figure 7); through this sleeve d^5 there passes a transverse shaft k^1 fast with a lever k and pivotally connected at each of its ends to a double link k^2 , itself pivotally connected to an arm k^3 , which can pivot about a fixed point k^4 on the chassis e of the carriage (Figures 6 and 7).

When the lever k has been pivoted to the left (position represented in Figures 4 and 6), the rear lip d^3 of the trough rests on the ground; when it is desired to raise this lip of the trough, for example in order to shift the shoveller, it is sufficient to turn down the lever k completely to the right, so as to bring it into the position represented in Figure 5; the articulated system k, k^1, k^2, k^3 acts, through the intermediary of the sleeve d^5 , on the bottom of the trough d so as to raise the latter; the lever k can be held in the lower position (and consequently the trough in its raised position) by a bolt k^5 , which can slide in a socket e^1 , connected, for example by welding, to the chassis e of the carriage; in its drawn-out position (Figure 5), this sliding bolt k^5 covers the lever k and prevents it from riding under the action of the weight of the trough.

The carriage comprises four wheels, of which the two front wheels e^2, e^2 (to the right in the drawing) are mounted on a pole-socket e^3 with pivot e^4 ; the rear wheels e^5 are angularly adjustable; they can be fixed (as shown in Figure 4) in three positions, by means of a pin e^6 , which is engaged in one of the three holes formed in a plate e^7 (fast with the chassis of the carriage). This arrangement permits of placing the shoveller in any desired angular position in relation to the heap of material to be removed, or of shifting it parallel thereto.

This shoveller is used in the following manner:

At the commencement of the operation, the beam having been raised by operation of the hand wheel i^8 , to an angle equal to the inclination of the bank of material to be removed, the shoveller is advanced towards this bank. The motor h^6 is set in operation; the scrapers g^1 of the chain g commence to scrape the heap of material. The cable i^8 is unwound, by operation of the hand wheel i^8 in the opposite direction to formerly, in order to permit the beam a to descend and to let the scraper chain g rest upon the heap. The material removed by the chain is brought to the bottom of the heap. Then it is carried by the scrapers g^1 to the one end of the trough and is picked up by the scrapers and carried through the trough. At the raised or discharge end of the trough, the material is discharged.

What I claim is:

1. A mechanical shoveller comprising a carriage serving for shifting of the shoveller as a whole, a trough mounted on said carriage, a scraper chain, two beams supporting said scraper chain, one beam extending within the trough and the second beam extending beyond the

trough causing a part of the chain to work within the trough while another part is scraping material from the ground up into the trough, means pivotally connecting the end of said one beam to one end of the second beam, 5 means pivotally connecting the other end of said second beam to the trough, a drive sprocket and a tensioning roller mounted on remote ends of said beams, a guide roller on each beam adjacent the pivotal connection of said beams for said scraper chain, said scraper chain passing over said sprocket and said tensioning roller and said guide rollers.

2. A mechanical shoveller comprising a carriage serving for shifting of the shoveller as a whole, a trough mounted on said carriage, a scraper chain, two beams 15 supporting said scraper chain, one beam extending within the trough and the second beam extending beyond the trough causing a part of the chain to work within the trough while another part is scraping material from the ground up into the trough, means pivotally connecting the end of said one beam to one end of the second beam, 20 means pivotally connecting the other end of said second beam to the trough, a tensioning roller mounted on a spindle on one of said beams, and discs with cutting edges mounted on the ends of said spindle to slice into the material to be picked up by the scraper chain.

3. A shoveller as claimed in claim 1 having discs with cutting edges mounted on the spindle of the tensioning roller to slice into material to be picked up by the scraper chain.

30 4. A shoveller as claimed in claim 1 having means pivotally connecting the trough to the carriage to enable raising and lowering movement of the trough on the carriage, and means on the shoveller for raising or lowering the trough and causing the lip of the trough to rest on or to be elevated above the ground, at will.

35 5. A shoveller as claimed in claim 1 having stops adjustably mounted on the trough in the vicinity of its pivotal connection with said second beam to limit the descending movement of said second beam and to prevent the chain from catching on the lip of the trough where the chain enters the trough.

6. A shoveller as claimed in claim 1 having means on the carriage to raise said exteriorly-extending second beam to shorten the length of the machine and facilitate 45 transportation.

7. A shoveller as claimed in claim 1 having wheel means at one end of the carriage pivotally mounted for angular turning, and wheel means pivotally mounted at the other end of the carriage for individual turning angularly relative to each other.
